UNITED STATES PATENT OFFICE.

WILLIAM ROBERTSON, OF CHICAGO, ILLINOIS.

CONVEYER.

1,378,901.

Specification of Letters Patent. Patented May 24, 1921.

Application filed July 8, 1917. Serial No. 178,488.

To all whom it may concern:

Be it known that I, WILLIAM ROBERTSON, a citizen of the United States, and a resident of the city of Chicago, in the county of Cook and State of Illinois, have invented certain new and useful Improvements in Conveyers; and I do hereby declare that the following is a full, clear, and exact description of the same, reference being had to the accompanying drawings, and to the numerals of reference marked thereon, which form a part of this specification.

This application is directed to that class of mechanisms shown in my issued Patent No. 822,153, for "material and cinder pit elevators", dated May 29, 1906.

This invention relates to an improved type of conveyer particularly adapted for use in conveying and elevating ashes, cinders or other material to a car to receive the same, as for instance, at a power plant station where ash handling is a considerable factor in the operation of the plant. Many different methods have been devised for handling the ashes or cinders at large power plants, and generally different types are adapted for different installations according to the conditions of operation as well as situation of the plant. This invention relates to that type of conveying mechanism wherein a dump car is utilized to receive the cinders when disposed on a track in a pit provided for the purpose, then elevated on the inclined track to dumping position to discharge the cinders for instance into a car on a siding.

It is an object therefore of this invention to construct a conveying system for handling ashes, cinders, or other material comprising an inclined track with a dump car adapted to be operated thereon from a receiving position in a pit to a dumping position over a railway car or other receiving means, by suitable mechanisms provided for the purpose.

It is also an object of this invention to construct a conveyer comprising an inclined track leading from a pit to a point elevated above the railway car, and equipped with a dump car adapted to be drawn from the pit to a position over the railway car to discharge the contents of the dump car thereinto, and with a cylinder movable with respect to a stationary piston and provided with means connected to the car to haul the car upwardly on the inclined track and act

as a counterweight therefor during return movement of the car to its receiving pit.

It is also an object of this invention to construct a conveying system embracing an inclined track leading from a pit to a point above a railroad siding upon which a receiving car may be switched, and with a dump car mounted on said inclined track adapted to be pulled upward from the pit to dumping position over the railway car by a movable pressure actuated cylinder moving with reference to a fixed piston, connected to operate said dump car, and acting as a counterweight therefor when the car is allowed to descend to its initial position in the pit.

It is finally an object of this invention to construct an improved type of conveying mechanism embodying a car movable upon an inclined track due to movement of a cylinder which acts as a counterweight for the car, the cylinder moving with reference to a fixed piston under the control of valves governing the flow of fluid into the cylinder.

The invention (in a preferred form) is illustrated in the drawings and hereinafter more fully described.

In the drawings:

Figure 1 is a side view partly in section and partly in elevation of a conveying device constructed according to the principles of my invention.

Fig. 2 is an end view of the structure illustrating the movable power cylinder mounted therein.

Fig. 3 is a central sectional view taken through the power cylinder in a lowered position with parts shown in elevation.

Fig. 4 is a top plan view of the power cylinder and its associated sheaves.

Fig. 5 is a detail section taken on line 5—5 of Fig. 3.

As shown in the drawings:

The reference numeral 1, indicates as a whole an inclined track, the lower end of which terminates in a pit 2, constructed beneath a railroad track 3, and the upper end of which is supported by an upright frame structure consisting of side uprights 4, with inner guide channel upright members 5, connected thereto by sway bracing 6, and further reinforced by transverse members where necessary. Said track 1, is also supported intermediate the framework 4—5, and in the pit 2, by an upright frame stanchion 7. A small dump car 8, adapted to run upon the inclined track 1, is provided with

a hinged bottom 9, with a small track wheel 10, on the forward end thereof which tracks upon an auxiliary center rail 11, between the rails of the track 1, and leading upwardly therewith to near the upper end thereof and inclining downwardly thereat as clearly shown in Fig. 1. Thus when the car is drawn into the dotted line position shown in Fig. 1, the wheel 10, rolling downwardly on the bent end of the track 11, will cause the hinged bottom of the car to swing downwardly, thus dumping the contents of the car through the bottom thereof. The track rails 13, of a railway siding are disposed between the stanchions 7, and the frame structure 4—5, so that a railway car 14, may be switched into position beneath the inclined track 1, to receive the contents of the dump car 8, as clearly shown in Fig. 1.

Journaled at the upper end of the structure 4—5, between the guide members 5, are a pair of sheaves 15 and 16, respectively, and disposed to slide between said uprights 5, is a cylinder 17, provided with guiding lugs 18, on the exterior surface thereof at opposite sides at each end of said cylinder to engage with the channeled guide frame members 5. Secured upon the upper end of the cylinder 17, are bearing brackets 19, in which are journaled a pair of sheaves 20 and 21, respectively, and secured to the upper end of the cylinder 17, and trained about the respective sheaves 15, 16, 20 and 21, is a cable 22, the other end of which is provided with a yoke 23, in which is journaled a pulley wheel 24, which is engaged on a curved rod 25, secured at the front end of the dump car 8. Secured in upright position between the side channels 5, is a stationary pipe or piston rod 26, which extends through a packing gland 27, in the lower end of the movable cylinder 17, and on its interior within said cylinder, is provided with a stationary piston 28. Just below said piston 28, said tubular piston rod is provided with openings or apertures 29, for the admission of air or steam under pressure into said cylinder. Any suitable admission and release valve or valves may be connected to the lower end of the pipe line 26, though none is shown, but since these types of valves are well known, it is not deemed necessary to illustrate the same.

55 The operation is as follows:

The normal position of the parts of the conveyer system is that shown in full lines

in Fig. 1, that is, with the dump car 8, disposed on the track 1, in the pit 2, and the cylinder 17, at the upper end of the frame 4—5. When it is desired to elevate the dump car 8, to dumping position, steam or air under pressure is admitted into the cylinder 17, through the stationary piston rod 26, the steam or air flowing through the apertures 29, thereof, into the interior of the cylinder beneath the stationary piston 28, so that the cylinder 17, is caused to slide downwardly in its guides 5, thereby drawing the cable 22, through the power reduction sheaves to elevate the dump car on its track, so that the fifth wheel 10, supporting the hinged bottom 9, thereof may swing downwardly at the curved end of the rail 11, permitting the contents of the dump car 8, to fall into the railway receiving car 14. The valve or valves controlling the flow of fluid into the cylinder 17, are then turned to release position to relieve the pressure in the power cylinder and the car 8, returns to its receiving pit by gravity, counterweighted by the weight of said cylinder 17.

I am aware that various details of construction may be varied through a wide range without departing from the principles of my invention, and I therefore do not purpose limiting the patent granted otherwise than necessitated by the prior art.

I claim as my invention:

In a conveyer, a vertical cylinder, a piston in said cylinder, a hollow rod supporting said piston, an inlet from the interior of said rod into said cylinder just below said piston, a packing box in the lower end of said cylinder through which said rod passes, guides on the exterior of said cylinder and stationary vertical guideways coöperating therewith, sheaves supported on the upper end of said cylinder, and coöperating sheaves supported above the first named sheaves by said guideways, and a cable working over said sheaves whereby on admission of fluid under pressure into said hollow rod, the cylinder will descend and a pull be exerted on said cable.

In testimony whereof I have hereunto subscribed my name in the presence of two subscribing witnesses.

WILLIAM ROBERTSON.
